(57) **CLAIM**

The ornamental design for a faucet spout, as shown and described.

DESCRIPTION

FIG. 1 is a perspective view of a faucet spout showing a new design;

FIG. 2 is a front view thereof;

FIG. 3 is a back view thereof;

FIG. 4 is a top view thereof;

FIG. 5 is a bottom view thereof; and,

FIG. 6 is a right side view (the left side view being a mirror image) thereof.

The broken lines in the Figures are for illustrative purposes only and form no part of the claimed design.
